UNITED STATES PATENT OFFICE

139,538

DESIGN FOR AN ASH TRAY

Millard F. Comstock, Fort Erie, Ontario, Canada

Application September 21, 1944, Serial No. 115,389

Term of patent 14 years

(Cl. D85—2)

Fig. 1 is a perspective of an ash tray embodying my new design; and

Fig. 2 is a side elevation thereof partially broken away to show interior features.

I claim:

The ornamental design for an ash tray, as shown.

MILLARD F. COMSTOCK.

To all whom it may concern:

I, Millard F. Comstock, a citizen of the United States, residing at Fort Erie, in the Province of Ontario and Dominion of Canada, have invented a new, original, and ornamental Design for Ash Tray, of which the following is a specification, reference being had to the accompanying drawing forming part thereof.
